METHOD OF ASSEMBLING RECEPTACLE
CLOSURE CAPS

John A. Johnson, Woodhaven, N. Y.

Application February 1, 1937, Serial No. 123,508

5 Claims. (Cl. 113—80)

This invention relates to assembling receptacle closure caps of the type known as "Crown caps" with a sealing pad of yielding material, such as cork or cork composition, having secured 5 to its exposed face a center spot of suitable non-absorbent, gas impervious and acid resistant material, such as metallic foil or paper having a coating of varnish on one surface, and of sufficient size to protect the sealing pad from the deleterious action of the acid and gas of the 10 contents of the receptacles to which the closure caps are applied.

It is an object of this invention to provide an improved method of assembling spotted sealing pads in closure caps which will assure an intimate bonding of the spots to the sealing pads and the sealing pads in the closure caps at a 15 high speed of production.

It has hereto been the practice to assemble and 20 adhesively secure the sealing pads in the closure caps, and later, after the adhesive securing the sealing pads to the closure caps has hardened and set, applying and adhesively securing the spots to the exposed surface of the pads assembled in the closure caps by heat and pressure. The heat and pressure used in securing or bonding the spots to the sealing pads will affect and 25 loosen the adhesive bond between the sealing pads and the closure caps, and permit the sealing pads with the center spots attached thereto to leave the closure caps before the caps are applied to the receptacles.

It is another object of the invention to overcome this disadvantage of the present practice 30 of assembling spotted sealing pads in closure caps by simultaneously or in continuous sequence adhesively uniting spots to sealing pads and adhesively uniting the sealing pads having center spots assembled thereon to the closure caps.

40 In the drawing accompanying and forming a part of this application

Figure 1 is a plan view of means for carrying out the method forming the embodiment of this invention.

45 Figure 2 is a sectional view of the means shown in Figure 1 taken on the line 2—2 of Figure 1 looking in the direction of the arrows.

Figure 3 is a sectional view of the means shown 50 in Figure 1 taken on the line 3—3 of Figure 1 looking in the direction of the arrows.

Figure 4 is a sectional view of modified means for carrying out the invention wherein a sealing pad simultaneously or in successive sequence with 55 the applying of a spot to a sealing pad is as-

sembled in a closure cap, and showing the parts in normal position; and

Figure 5 is a view similar to Figure 4 but showing the parts in position after the spot has been applied to a sealing pad and the sealing pad assembled in a closure cap. 5

In carrying out the invention in accordance with the embodiment illustrated in Figures 1 to 3, inclusive, closure caps C of the crown type having deposited therein an adhesive non-viscous at normal or room temperature and adapted to be rendered viscous and tacky by an elevated temperature, are supported at the marginal portions and transported or conveyed in a linear or circular path and maintained in predetermined spaced relation by suitable means, not shown, with the tops of the closure caps lowermost below a pair of spaced members 4' shown as disposed at opposite marginal portions of the flared skirts of the closure caps to maintain the closure caps in flat condition on the closure cap transporting or conveying means. The closure caps are transported in the direction as shown by the arrow in Figure 1 through a zone of elevated temperature produced by suitable means 20 and shown as a gas burner 5' having the gas discharge orifices positioned below and disposed relative to the path of travel of the closure caps to direct the gas flame against the tops of the closure caps and render the adhesive in the closure caps viscous and tacky, as shown at the left of Figure 2. 25

Simultaneously with the transporting of the closure caps, sealing pads P formed of comminuted cork bonded together in a compressed mass 35 by suitable bonding material, or of solid cork, are transported along a flat support 6 by suitable means, not shown, which maintain the pads in spaced relation to each other and feed the sealing pads in a direction to intersect the path 40 of travel of and align the sealing pads in superposed relation to the closure caps as indicated by the arrow in Figure 1. The support 6 extends in a direction transversely of and over the path of travel of the closure caps, as shown in 45 Figures 1 and 3. The sealing pads are passed through a zone of elevated temperature spaced from the path of travel of the closure caps and produced by suitable means shown as being an electric heating element 7 of suitable design extending above and in spaced relation to the travel of the sealing pads on the support 6. 50

The sealing pads are heated to render viscous and tacky an adhesive surface of spots S of non-absorbent, gas impervious and acid resistant ma- 55

terial, such as tin or aluminum foil, or varnished paper, adapted to be contacted with the sealing pads. The spots S are severed from a composite web W having one surface coated with an adhesive non-viscous and non-tacky at normal or room temperature and adapted to be rendered viscous and tacky when subjected to an elevated temperature, and the other surface comprising a metallic foil or paper having a varnish coated surface, and which composite web may be formed by the method and apparatus disclosed in my Patents No. 1,949,419 and No. 1,949,420 issued March 6, 1934. The composite web W is fed from a roll, not shown, in spaced relation above and to intersect the travel of the sealing pads, and shown as being fed in the same direction as the travel of the closure caps, but said direction of travel of the composite web may be in the opposite direction without affecting the method of assembling. The composite web W is fed from the roll in a horizontal plane with the adhesive surface lowermost by suitable means, shown as a pair of feed rollers 8, relative to a die 9 arranged in a plate 16 mounted in spaced relation to the upper surface of the support 6 and adjacent the heating element 1, and a punch 10 reciprocatory relative to the die and co-operating therewith to sever a disk or spot S from the web and position said severed spot centrally of a heated pad P which has been advanced from the heating element, with the adhesive surface of the severed spot in contact with the heated pad. The heat of the pad will render said adhesive surface viscous and tacky and the pressure of the punch will effect adhesion between the spot and pad. The web is positioned and guided centrally of the punch and the die to assure the severing of a spot from the web by a plate 11 of channel form in cross section mounted on the die plate 16 and having an opening 12 therein slightly larger than and in line with the punch and die.

The spots S are of a diameter less than the diameter of the sealing pads but of sufficient area to completely cover that portion of the face of the sealing pads which will be exposed to the deleterious action of the contents of the receptacles to which the closure caps are adapted to be applied. The sealing pads having the protective spots bonded to the face thereof in the manner hereinbefore described may be stacked in a magazine and stored in such condition until required for assembling in the closure caps C, and to intimately unite the spots to the sealing pads until such requirement arises, a pad having a spot adhering thereto is advanced along the support 6 from the die 9 to position relative to a plunger 13 reciprocatory toward and away from said pad and spot and arranged with an electric heating element 14 to heat said plunger to a sufficiently high temperature whereby heat and pressure is applied to the pad and spot when the plunger engages the spot to effect intimate adhesion between the spot and pad, the plunger being of a diameter to engage only the spot and prevent the scorching of the pad. The plunger 13 is guided to engage centrally of the spot by an opening 15 in an extension of the die plate 16.

To assemble sealing pads with spots assembled thereon in the closure caps the sealing pads with spots assembled thereon are transported on the support 6 from the spot severing plunger 10 to and in registry with a tapered opening 17 in the support 6 in alignment with the travel of the closure caps and relative to which opening 17

and an opening 18 in the plate 16 a plunger 19 is reciprocated to engage the sealing pad with the spot thereon and position the same in a closure cap with the pad in contact with the viscous and tacky adhesive in said closure cap. The support 6 and plate 16 are located adjacent the burner 5 so that the adhesive in the closure caps is fully viscous. The bonded spot and pad may be subjected to heat and pressure to effect intimate adhesion between the spot and pad prior to assembling in the closure cap by presenting the spot assembled on a pad to the heated plunger 13 prior to the assembling of said pad in the closure cap by the plunger 19, but this is not necessary as the pressure of the plunger 19 and the heat of the pad and closure cap will effect an intimate adhesion between the spot and pad.

Instead of transporting the sealing pads with spots assembled thereon on the support 6 and positioning said sealing pads in registry with the opening 17 in said support and assembling the sealing pads with spots assembled thereon in closure caps transported relative to the opening 17 in the support 6 by the plunger 19, the heated closure caps may be transported parallelly of the direction of travel of and below the web W and to intersect the support 6, as shown in Figures 4 and 5, or they may be transported parallelly of and below the support 6. In either case, the support 6 is provided with the opening 17 in registry with the die opening 9 in plate 16, whereby when a spot is severed from the web W and applied to a sealing pad, the sealing pad simultaneously or successively with the severing of the spot from the web and applying of the severed spot to the sealing pad, is assembled by the punch 10 in a closure cap transported relative to and positioned in registry with said opening 17 in the support 6 and the die opening 9 in plate 16, as shown in Figure 5.

To assure an intimate adhesion between the spot and pad and the pad and closure cap, the closure cap having the composite spot and pad assembled therein is transported from the punch 10, or the plunger 19, to means to apply heat and pressure which may be in the form of a heated plunger 20 reciprocatory mounted adjacent to the plunger 19 and may comprise an electrically heated plunger similar to the plunger 13. After the sealing pads with spots assembled in closure caps are subjected to the heated plunger 20 they are subjected to pressure during the cooling period, and shown as a series of spring actuated plungers 21 succeeding the plunger 20 adapted to engage the spots and apply pressure to the spots and pads assembled in the closure caps, as shown in Figure 2. It may be desirable to omit the heated plunger 20, as the closure cap may be heated to such a degree to emit sufficient heat to transmit the same to the union between the spots and pads.

Having thus described my invention, I claim:

1. The method of assembling closure caps with a sealing pad having a center spot on its exposed face, which comprises providing closure caps having an adhesive therein, heating sealing pads, applying a spot having an adhesive surface non-viscous at normal temperature and adapted to be rendered viscous when subjected to an elevated temperature centrally of and with the adhesive surface thereof in contact with a heated pad, the heat of the pad rendering the adhesive surface viscous and causing the spot to adhere to the pad, and assembling the heated pad with the spot applied thereto in a closure cap with the pad

in contact with the adhesive in said closure cap to secure the pad and spot to the closure cap.

2. The method of assembling closure caps with a sealing pad having a center spot on its exposed face, which comprises providing closure caps having an adhesive therein, heating sealing pads, applying a spot having an adhesive surface non-viscous at normal temperature and adapted to be rendered viscous when subjected to an elevated temperature centrally of and with the adhesive surface in contact with the heated pad, subjecting the composite spot and pad to heat and pressure to effect an intimate adhesion between the spot and pad, and then assembling the heated composite spot and pad in a closure cap with the pad in contact with the adhesive in said closure cap to secure the composite spot and pad in the closure cap.

3. The method of assembling closure caps with a sealing pad having a center spot on its exposed face, which comprises providing closure caps having adhesive non-viscous at normal temperature deposited therein, heating sealing pads, feeding a web of spot material having an adhesive surface non-viscous at normal temperature relative to the heated sealing pads with the adhesive surface facing said heated sealing pads, severing spots from the web and applying the spots as they are severed from the web to the heated pads with the adhesive surface in contact with the heated pads to render said surface viscous and attach the spots to the sealing pads, heating the closure caps to render the adhesive therein viscous, and assembling the heated sealing pads with spots applied thereto in the heated closure caps with the sealing pads in contact with the viscous adhesive in the closure caps.

4. The method of assembling closure caps with a sealing pad having a center spot on its exposed face, which comprises providing closure caps having an adhesive therein, heating sealing pads, feeding a web of spot material having an adhesive surface non-viscous at normal temperature

relative to the heated sealing pads with the adhesive surface facing said heated sealing pads, severing spots from the web and applying the spots as they are severed from the web centrally of the heated pads with the adhesive surface in contact with the heated sealing pads to render viscous the adhesive surface and attach the spots to the sealing pads, subjecting the attached spots and sealing pads to heat and pressure to effect an intimate adhesion between the spots and sealing pads, assembling the heated sealing pads having spots centrally thereon in closure caps with the sealing pads in contact with the adhesive in the closure caps, and placing the assembled closure caps under heat and pressure to effect an intimate adhesion between the sealing pads and the closure caps.

5. The method of assembling closure caps with a sealing pad having a center spot on its exposed face, which comprises providing closure caps having an adhesive non-viscous at normal temperature therein, sealing pads and a web of spot material having an adhesive surface non-viscous at normal temperature, transporting the closure caps through a zone of elevated temperature to render the adhesive therein viscous, transporting the sealing pads through a zone having an elevated temperature and to intersect the travel of the closure caps, feeding the web of spot material transversely above the travel of the sealing pads with the adhesive surface facing the heated sealing pads, severing spots from the web and applying the severed spots to the heated pads with the adhesive surface in contact with the heated pads, assembling the heated sealing pads and the spots applied thereto in the heated closure caps with the sealing pads in contact with the viscous adhesive in said closure caps, and placing the assembled closure caps under pressure to effect an intimate adhesion between the spots and sealing pads and the sealing pads and closure caps.

JOHN A. JOHNSON,
